CLAIM

The ornamental design for a headlight mask carrier for a motorcycle as shown.

DESCRIPTION

FIG. 1 is a left side view of a headlight mask carrier for a motorcycle showing the new design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a front perspective view thereof;

FIG. 8 is a rear perspective view thereof; and,

FIG. 9 is another rear perspective view thereof.

The broken lines shown illustrate portions of the headlight mask carrier for a motorcycle that form no part of the claimed design.

1 Claim, 9 Drawing Sheets
